PORTABLE RIVETER

Patrick B. Tisie, Detroit, Mich.

Application March 27, 1944, Serial No. 528,229

3 Claims. (Cl. 78—46)

1

The present invention relates to portable riveting machines.

The primary object of the invention is to provide a portable riveter having means for clamping the work prior to the riveting operation so that the pieces of work will be united in face-to-face contact and will be held in this position during the upsetting of the rivet.

Another object of the invention is to provide a portable riveter having a work-engaging clamp which is projected simultaneously with the plunger so as to engage the work first before the plunger upsets the rivet and to provide resilient spring means to permit the movement of the plunger relative to the clamping sleeve after the same has engaged the work in the vicinity of the rivet being set.

Another object of the invention is to provide a riveting machine of the above-mentioned type having means for permitting adjustment of the strokes to facilitate the use of the riveter with rivets of various lengths.

Another object of the invention is to provide a resilient spring means for retracting a rivet plunger and the clamping sleeve after the rivet has been set in the work.

Other objects and advantages will become apparent during the course of the following description of the accompanying drawing, wherein:

Figure 1 is a side elevational view of a riveting machine showing portions thereof broken away to illustrate the various structural details thereof and to show the manner in which the work is held in the riveter between the jaws thereof prior to the rivet-upsetting operation;

Figure 2 is a longitudinal cross sectional view taken on line 2—2 in Figure 1 looking in the direction of the arrows showing the rivet plunger and clamping sleeve, retracting means and showing the manner in which the stroke of the rivet plunger may be adjusted to accommodate rivets of various lengths;

Figure 3 is a transverse cross sectional view taken on line 3—3 in Figure 1 looking in the direction of the arrows further illustrating the manner in which the stroke of the rivet plunger may be adjusted for accommodating rivets of various lengths; and

Figure 4 is a fragmentary side elevational view similar to Figure 1 showing the clamping sleeve in its opposite position and the rivet plunger in position to upset the end of the rivet.

In the drawing, wherein for the purpose of illustrating the invention like reference characters will be employed to designate like parts through-

2

out, the reference character 5 will generally be employed to designate a casing or housing of a portable riveter including a handle portion 6, and a hollow casing section 7 having spaced walls 8 connected to the top and bottom by parallel walls 10. The side walls 8 are extended as at 12 to provide spaced ears 13 between which is received a yoke member 14 having jaw portions 15 and 16. Bolts 17 extend through suitable apertures in the ears 13 and the yoke frame 14 and nuts 18 are threaded on the bolts to securely hold the yoke frame 14 in place relative to the casing 7 and handle portion 6. The yoke frame 14 has an opening 19 formed in the jaw portion 15 for receiving a removable anvil 20 recessed as at 21 to receive the head of a rivet R which, as shown in Figure 3, has been passed through openings in the overlapped work pieces W. The other jaw portion 16 of the yoke frame 14 is provided with a bore 22 in axial alignment with the anvil 20 and said bore is fitted with a work-clamping sleeve 23 having its work-engaging end 24 projecting slightly beyond the edge of the jaw 16 in the direction of the work W.

Slidably mounted within the work-clamping sleeve 23 is a rivet plunger 25 and said sleeve 23 is provided with longitudinal slots 26 arranged in diametrically opposed relation for receiving a transverse pin 27 fitted in the end of the rivet plunger 25. The rivet plunger 25 may slide relative to the sleeve 23 between the limits of the slot length 26 as indicated in Figure 1. The inner ends of the sleeve 23 and rivet plunger 25 project into the housing 5 between the side walls 8 thereof and the extreme inner end of the rivet plunger 25 is provided with an axially threaded bore 29 for receiving an adjusting screw 30 having an enlarged head 31. A slotted washer 32 may be interposed between the extreme inner end of the rivet plunger 25 and the head 31 of the adjusting screw so as to project the rivet plunger beyond a predetermined distance and permit the riveting machine to be used with rivets of various lengths. By substituting slotted washers 32 of different thicknesses, between the inner end of the rivet plunger 25 and the head 31, said rivet plunger may be made to project corresponding distances and accommodate rivets of different lengths and different sizes.

Encircling the inner end of the rivet plunger 25 is a coil spring 34 having one end in abutting relationship with the inner end of the work clamping sleeve 23 and the other end in abutting relationship and engagement with the slotted washer 32.

Pivotedly mounted within the housing 5 is an operating lever 37 carried on a pivot pin 38 and said operating lever 37 is bifurcated at one end for receiving a roller or the like as at 39 pivotally mounted on a stub pin 40. Formed integral with the operating lever 37 is a cam projection 41 which is presented to the adjusting screw 31 so as to project the rivet plunger and work clamping sleeve 23 when air pressure is admitted to the riveter and the pivoted lever 37 swung on its pivot 38 by means of a cam operator 43 having its cam face 44 in contactual engagement with the roller 39. In squeeze type riveters in which the rivet is compressed, the cam bar 43 is usually connected to the plunger of a fluid compression system and said plunger is mounted in a cylinder communicating with a source of pressure so that admission of pressure to the cylinder will move the piston toward one end and cause the cam arm 43 to project into the housing 5 and through the handle portion 6 so as to depress the pivoted lever 37 by the contactual engagement of the cam surface 44 with the roller 39.

The adjusting screw head 31 is provided with a series of circumferentially spaced radially extending slots 46 for receiving a tool or the like to facilitate adjustment of the head and the backing off of the screw for the insertion of a slotted washer 32 of increased or decreased thickness.

The rivet plunger 25 and clamping sleeve 23 are retracted by means of coil springs 50 disposed on each side thereof and one end of each coil spring is attached to a pair of oppositely arranged screw studs 51 in the inner walls 8 of the housing 5 while the opposite ends of the screws are hooked over threaded studs 52 as at 53 extending in diametrically opposed relation from one end of the sleeve 23.

In operation, the work W is placed on the anvil 20 in overlapping relation, with the apertures therein in registry and the rivet R received therein with the head of the rivet arranged in the annular recess 21. The pressure control valve of the riveter (not shown) is then operated to project the cam arm 43 in a straight line path so that the cam surface 44 will engage the roller 39 and rock the cam lever 37 on its pivot 38. Upon rocking movement of the cam lever 37 the cam projection 41 is moved into engagement with the head 31 of the screw 30 so as to project the clamping lever 23 and rivet plunger 25 simultaneously until the end 24 of the sleeve engages the work W. When the end 24 of the sleeve engages the work, the overlapping ends thereof will be clamped together so that the meeting faces thereof will be in mutual engagement so that continued operation of the cam lever 37 will cause the plunger 25 to move relatively to the sleeve 23 and compress the spring 30 so as to clamp the work under spring tension. After the clamping sleeve 23 has been moved into clamping engagement with the work W as shown in Figure 4, the end of the rivet plunger 25 moves into engagement with the rivet R and the socket or recess 55 in the end thereof engages the end of the rivet and causes the same to be upset. Upon retraction of the cam arm 43 the springs 50 move the sleeve 23 and plunger 25 to their initial starting position. When it is desired to shorten or lengthen the stroke of the rivet plunger to accommodate rivets of various sizes, the bolts 17 and nuts 18 connecting the yoke 14 with the housing 5 may be removed so that the head of the bolt 31 may be untightened and a

slotted washer 32 of different thickness inserted in lieu of the one previously used.

It is to be noted that the transverse pin 27 operates in the bore 22 of the jaw 16 and during the major portion of the time the slots and pin 26 and 27 are confined within said bore to be removed from the path of foreign matter and obstructions.

It is to be understood that the form of the invention herewith shown and described is to be taken as a preferred embodiment thereof and that various changes in the shape, size and arrangement of parts may be made without departing from the spirit of the invention or the scope of the subjoined claims.

What I claim is:

1. A portable riveting machine, comprising a casing, a removable yoke frame connected to the casing having spaced jaws, a rivet anvil mounted in one of the jaws, a work clamping sleeve slidably mounted in a bore in the other jaw in opposed relation to the rivet anvil, a rivet plunger slidably mounted in the sleeve, a pin and slot connection between the plunger and sleeve to permit limited longitudinal movement therebetween, a coil spring encircling the inner end of the plunger having one end engaging the inner end of the sleeve, a retaining screw threaded in the inner end of the plunger having an enlarged head for receiving the thrust of the other end of the coil spring, a removable slotted washer interposed between the head of said screw and the end of the plunger to increase or decrease the distance between the rivet plunger and rivet anvil and for engaging the other end of the screw, means within said casing for projecting the plunger, and resilient means connecting the sleeve and casing for retracting the sleeve and plunger.
2. A portable riveter comprising a casing, a yoke frame secured to said casing and having spaced jaws, a rivet anvil mounted on one of said jaws, a rivet plunger member slidably mounted in the other jaw in axial alignment with the anvil, mechanism including a driving member within said casing engageable with said plunger for urging said plunger into engagement with a rivet and the work respectively resting against said anvil, an axially adjustable abutment element disposed between said members and having an extension connected to one of said members in axially-spaced relationship thereto, and a spacing element inserted in and filling the space between said abutment element and the member to which it is connected and having an aperture therein receiving said extension whereby to adapt said riveter to varying lengths of rivets by interchanging spacing elements of different thickness in said space.
3. A portable riveter comprising a casing, a yoke frame secured to said casing and having spaced jaws, a rivet anvil mounted on one of said jaws, a rivet plunger member slidably mounted in the other jaw in axial alignment with the anvil, mechanism including a driving member within said casing engageable with said plunger for urging said plunger into engagement with a rivet and the work respectively resting against said anvil, an axially adjustable screw-threaded abutment element disposed between said members and having a shank threaded into one of said members in axially-spaced relationship thereto, and a spacing element inserted in and filling the space between said abutment element and the member to which it is connected

and having an aperture therein receiving said shank whereby to adapt said riveter to varying lengths of rivets by interchanging spacing elements of different thickness in said space.
